[57] CLAIM

The ornamental design for a frame neck cover for a motorcycle, as shown and described.

DESCRIPTION

FIG. 1 is a side elevational view of a frame neck cover for a motorcycle showing my new design, the broken lines are for illustrative purposes only and form no part of the claimed design;

FIG. 2 is a perspective view thereof;

FIG. 3 is a front elevational view thereof;

FIG. 4 is a right elevational view thereof;

FIG. 5 is a rear elevational view thereof;

FIG. 6 is a left elevational view thereof;

FIG. 7 is a top plan view thereof;

FIG. 8 is a bottom plan view thereof; and,

FIG. 9 is perspective view of a second embodiment of FIG. 1, it being understood that the undisclosed perspective view opposite of that shown herein is a mirror image. It is also understood that the undisclosed top, bottom and side views are basically the same as in the first embodiment.
